UNITED STATES PATENT OFFICE.

EMILE LAMBOTTE, OF SALINA, KANSAS.

MUSICAL INSTRUMENT.

SPECIFICATION forming part of Letters Patent No. 752,080, dated February 16, 1904.

Application filed July 14, 1902. Serial No. 115,580. (No model.)

To all whom it may concern:

Be it known that I, EMILE LAMBOTTE, a citizen of the United States of America, residing at Salina, in the county of Saline and State of Kansas, have invented certain new and useful Improvements in Musical Instruments; and I do hereby declare that the following is a full, clear, and exact description of the invention, such as will enable others to make and use the same, reference being had to the accompanying drawings, forming a part of this specification.

The objects of my invention are, first, to secure the members of the body of a musical instrument together, so as to prevent their coming apart from climatic effects or the warping of these parts; second, to produce a bass tone of increased power and clearness in a stringed musical instrument.

The invention consists in the novel construction and combination of parts, such as will be first fully described and then specifically pointed out in the claims.

In the drawings, Figure 1 is an interior view in perspective of the body of the musical instrument with the front removed, showing the tongue upon the sides and the finger-board, the outer end of the finger-board being broken away. Fig. 2 is a plan view of the inner side of the front of the instrument, showing the grooves and the bass-sound strip. Fig. 3 is a longitudinal sectional view of the musical instrument. Fig. 4 is a transverse vertical sectional view taken upon line $z-z$ of Fig. 3. Fig. 5 is a transverse sectional view taken upon the line $y-y$ of Fig. 2.

Similar letters of reference indicate corresponding parts in all the figures of the drawings.

Referring to the drawings, A represents the component parts or members of the hollow body of a violin, represented by the back a , which is of the usual form, and the vertical sides a' and ends a'' , which are of the usual width.

B represents the sounding-board or belly, having the usual f -shaped holes or openings $b-b$.

C represents the neck of the violin, and c the finger-board.

At each end of the sides a of the violin and

forming a part of the inner surface of said ends are the blocks or extensions $a^3 a^3$, the inner surfaces $a^x a^x$ of which opposite each other are curved outwardly in the arc of a circle. The upper horizontal surfaces of the blocks $a^3 a^3$ are in the horizontal plane of the upper edges of the sides a' and ends a'' .

$a^4 a^4$ are the inwardly-curved portions or waist-line of the sides a' , the ends of the curved lines meeting at a point, the inwardly-curved lines a^5 terminating the outwardly-curved lines or scrolls a^6 of the sides a' at the ends of the violin. At the junction of these inwardly-curved parts $a^4 a^5$ of the sides a' they are integral also with the said sides. On the inner surface of the sides a' of the violin, extending downwardly a short distance in depth from the upper edge a^7 , is a rabbet or groove a^8 , which groove in both sides of the instrument extends below the upper surfaces of the curved portions $a^4 a^5$ of the waist-line and terminates with the inner surfaces $a^x a^x$ of the blocks $a^3 a^3$.

The sounding-board or belly B, which forms the front of the violin and which is fitted to the sides a , is made of considerable thickness on its inner surface adjacent to the outer edges, the width of the thickened portion b' being increased at each end of the board from the lines of said end and the sides of the belly having the ordinary extensions $b^3 b^3$ at the ends of the curved lines $b^2 b^2$, corresponding in position to the projections on the sides a' at the meeting-points of the inwardly-curved portions $a^4 a^4$ with outwardly-curved portions a^6 of said sides. In said thickened portion b' of the inner surface of the edge of the sounding-board is a groove b^4 , slightly wider than the upper edge a^7 of the sides a' of the instrument, which at each end of the board is extended in width, as at b^5 , and conforms to the curved surfaces a^3 of the blocks a^3 on the sides a' , and in the projections b^3 the lines of the grooves are extended in width, so as to conform to and receive the projections described in the sides a' of the body A of the violin.

D represents the bass bar, which is upon the inner side of the sounding-board B and extends in the longitudinal direction of the board to within a considerable distance from

the ends. Said bar is made integral with the sounding-board, the sides d extending downwardly and being inclined inwardly to a point, the ends a' inclining inwardly from both sides 5 and at an angle thereto. The bass bar is upon the side of the front or sounding-board over which the bass strings of the instrument are placed, said bar being arranged in position at an angle in a slight degree to an imaginary 10 line separating the board longitudinally into two equal parts.

In the block a^3 at the upper or smaller end of the violin is a dovetail mortise a^9 , extending through the side a' and downwardly 15 about two-thirds the distance from the upper surface of the block toward the back a . The inner end of the neck C is formed with a dovetail tenon c' to fit the mortise a^9 , forming an interlocking joint. The under surface 20 of the portion of the neck C , which is connected with the end of the violin, is curved downwardly, as at c^2 , in the ordinary manner.

The groove b^4 in the sounding-board or front B and also the groove a^8 in the side a' 25 of the body A are provided with glue. The parts are then fitted together, forming a close joint, the rabbet a^8 fitting around the under surface of the sounding-board B .

Thus constructed the instrument will stand 30 the changes incident to any climate and severe usage without liability of coming apart. The back a of the instrument may be connected with the sides in the same manner as the front or sounding-board, if preferred.

35 In the production of the musical tones from the bass strings of the instrument the vibrations of the sounding-board directly beneath the strings are modified by the bass bar, the tones being deepened, and this result is perfected by the integral nature of the bar with 40 the sounding-board, the tones depending for clearness upon the like texture of the material and the continuity of the grain. The bass tone of the violin is therefore highly improved 45 and a superior depth of the bass tone obtained.

I have shown the invention as applied to a violin as one instance of its use.

The invention is applicable to all stringed instruments made in separate parts or with a 50 body hollowed out, and with pleasing results.

Such modifications of the invention may be employed as are within the scope of the invention.

Having fully described my invention, what

I now claim as new, and desire to secure by Letters Patent, is—

1. In a musical instrument, a hollow body and a sounding-board therefor, and a tongue-and-groove joint connecting said parts together.

60 2. In a stringed musical instrument, the combination with a hollow body, and the upwardly-extended sides of said body, of a front having a groove in its inner surface registering with and adapted to receive the edge portion of said sides of the instrument.

65 3. In a stringed instrument, a hollow body having upwardly-extended sides and ends, and blocks on the inner surface of the ends of said body, a sounding-board having thickened edges, and a groove varying in width on the inner surface of said thickened edges registering with and adapted to receive the upper edge of said sides and ends and the upper surface of said blocks.

70 4. In a stringed instrument, a hollow body having sides and ends, and a rabbet in the inner surface of said sides and ends, and a sounding-board having a groove registering with and adapted to receive the upper edge of said 75 rabbeted sides and ends of the body.

75 5. In a stringed musical instrument, the combination with a hollow body, the sides and ends thereof having a rabbet in their inner surfaces, the blocks upon the inner surfaces 80 of the ends of said instrument having their upper surfaces in the plane of the upper edges of said ends, of a sounding-board having thickened edges, and a groove varying in width at the sides and ends of said board registering 85 with and adapted to receive the upper edge of said sides and ends and the said blocks, substantially as described.

6. A violin-body top having a straight bass bar extending longitudinally parallel to and 90 on one side of the middle line of the top, the bass bar being formed integrally with the top from a single piece of wood, as set forth.

7. A violin-body top having a straight bass bar extending longitudinally parallel to and 95 on one side of the middle line of the top, the bass bar being formed integrally with the top from a single piece of wood and terminating at a distance from each end of the top as set forth.

100 EMILE LAMBOTTE.
